STEAM HEATING SYSTEM.

Application filed February 23, 1924. Serial No. 694,526.

My invention relates to steam heating systems, and more particularly to the pumping and control mechanisms for maintaining a vacuum upon the radiators and for returning the water to the boiler.

As is well known to those skilled in the art, steam heating systems are now commonly in use employing steam at a relatively low boiler pressure and employing a vacuum 10 circulating pump for maintaining a circulation through the radiators and for withdrawing the condensate and waste steam mixed with air which leaks into the system. It is desirable to separate out the air, 15 condense the steam and return the condensate to the boiler, either directly or indirectly. It will be seen that there are a number of functions involved in this relatively complex problem. First, there is the necessity 20 for maintaining a vacuum upon the return line, and this vacuum must be maintained without discharging all of the gaseous fluid to atmosphere, because the gaseous fluid which comes from the return line contains 25 a large proportion of steam which is flashed to a vapor because of the reduced pressure. It has generally been found advisable to compress this gaseous fluid in order to condense the water vapor and separate the air 30 or other gases from the water and discharge the gases to atmosphere and return the condensate which is thus produced to the boiler. If all of the fluid or fluids which came from 35 the return line were in gaseous or vapor condition, then a relatively small high speed positive displacement pump, in the nature of a compressor, might be desirable, but the problem is complicated by the fact that liquid is also drawn from the return pipe, 40 and hence any positive displacement pump would have to operate at a speed suitable for handling liquid. This would require a relatively large slow speed pump not particularly suited to present day conditions. It 45 is desirable to employ an electric motor for work of this character, and this means a motor speed of approximately eighteen hundred (1800) revolutions per minute, hence a positive displacement pump is not satisfactory.

The art has developed into the use of pumps not of the positive displacement type, because of their compactness and relative

simplicity. That is to say, it is common now to employ some form of centrifugal pump 45 or pumps for producing and maintaining the vacuum in the return line of the steam heating system and to return the condensate to the boiler. Heretofore, the art has been successfully developed according to two 60 methods.

According to the first method, all of the condensate, flash steam and noncondensable gases are returned to a tank or receiver which is kept under the vacuum of the system. Here the gases and vapors separate 65 from the water, and the accumulated water is drawn off and returned to the boiler by a water pump which is usually of the centrifugal type. The gases are removed from the top of the receiver by a separate air or vapor pump and are discharged to atmosphere. Both pumps may be driven by one 70 electric motor, or individual drive may be provided. The "Nash" or "Jennings" system is typical of this mode of operation. 75

Such system is effective in operation, but requires an unnecessary complication of running parts and incorporates the inefficiency of two pumps. In addition, the 80 gaseous fluid is discharged into the atmosphere containing a considerable content of flash steam.

The second mode of operation employs one or two pumps, either or both of which 85 always handle water only. Water is drawn from a tank under atmospheric pressure and is forced through an ejector at high velocity. The suction side of the ejector is connected through a check valve to the return line, 90 and the entire flow of air and water in this line is induced by the high velocity of the circulation water. The mixture of air and water is delivered to the circulation tank, from which the air discharges to atmosphere. Water accumulates in the tank until sufficient is present to open a float operated valve, which permits either the circulation pump or a separate water pump to deliver the excess water to the boiler. The so-called "Young" system is typical of this mode of operation. One objection to this system is its extremely low efficiency due to the entire dependence upon the water operated ejector and the large amount of water which must be 100 wastefully handled during normal operation.

According to my invention, I depart from both of the prior modes of operation and secure a high efficiency of operation and relatively great simplicity of apparatus by 5 the employment of a peculiar form of pump and controlling apparatus, such as I shall hereinafter describe.

The pump which I employ is of the type disclosed in my co-pending application, 10 Serial No. 541,030, filed March 4, 1922.

A pump of this type will pump gas, vapor, or liquid, or a mixture of them, and produce a positive suction when pumping any of said fluids.

15 In the specification hereafter, I shall use the term "gas" to include both the water vapor and the gases, such as they are, which leak into the vacuum lines.

The pump, under a given set of conditions, 20 will handle its maximum capacity of air discharge when a certain ratio of gas to liquid is supplied to the intake of the pump. That is to say, if the ratio of gas to liquid in the intake of the pump, which I term herein the 25 "intake gas ratio", drops substantially below a predetermined value which is found to give maximum air displacement, the gas delivery drops because too much of the discharge is taken up by liquid. On the other 30 hand, if the gas ratio is too high, not enough liquid is present to entrain the air required and again the gas delivery drops.

Now, the gas ratio is affected in turn by the back pressure. If the head against 35 which the pump must deliver its discharge is high, then the gas ratio should be lowered and vice versa.

Now, the theory of operation of my present system is built around the desired characteristics of a proper gas ratio for the 40 pump. That is to say, the present system is automatically controlled by the three variables; namely, the flow of gas and the flow of liquid on the intake side and the back pressure on the discharge. The effect of 45 back pressure upon the gas ratio is easily comprehended in the compressibility of the gas and the incompressibility of liquid.

The operations and stages of action are all 50 designed to be performed at such times and in such manner as to provide the proper gas ratio for the pump.

Incidentally, I employ at a certain stage 55 of operation a gas ejector to raise the rate of gas discharge, but this is active only as a supplementary device to extend the range of gas delivery upon dropping the back pressure to atmosphere. Obviously, if the discharge pressure should drop below intake 60 pressure (and this actually does occur at one stage of operation), the rate of gas delivery would be limited only by the size of the connection. It is to take care of the special condition of an excess of gas on the intake side 65 and a low back pressure that I employ the

ejector. The ejector is to be regarded not as a primary operating unit, but as a secondary or auxiliary device which could be dispensed with if desired.

The thing to be considered primarily is 70 the action of the pump and the ways it is utilized to meet the varying conditions of gas, liquid and back pressure above referred to.

The pump is not claimed herein but is 75 claimed in my co-pending application, Serial No. 751,210, filed Nov. 21, 1924.

The procedure which I employ is briefly as follows: I utilize a chamber on the intake side which, under certain circumstances, 80 serves as a liquid trap. I employ a large chamber on the discharge side which serves normally as a gas separator. So long as a proper working intake gas ratio prevails, the pump takes gas and liquid and dis- 85 charges the same into the discharge tank or separating trap, where the gas is liberated or separated and discharged to atmosphere and the liquid separately discharged into the boiler, both under pressure. If now the intake gas ratio increases too much, I must do one of two things, or both; namely, either increase the liquid intake to restore the gas ratio or drop the discharge pressure to a point corresponding to the prevailing gas ratio, or a combination of both.

Now, it will be obvious that if the pump size were very great, then the absolute values of the gas ratio might vary considerably and the pump still be able to do its work, but in a system of this kind, economy of first cost and economy of operation must be carefully worked out. As I have above indicated, the device of my invention must satisfy three variables, and hence the operation is relatively complex. To make the device automatic, I provide suitable controls which depend for their operation upon the effect which the three variables have upon the pump.

I provide the pump with a vane which divides the discharge opening into two channels. Into each of these channels I set Pitot tubes facing against the outflow or current of the discharge of the pump. Controlling valves are operated in accordance with the pressures prevailing in said Pitot tubes. Said Pitot tubes are devices for measuring the impact of the liquid discharged from the pump. The impact pressure is a measure of the velocity and density of the fluid mixture flowing past them. By dividing the flow into two parts, I get a very sharp and positive definition of the discharge into two quantities, one of which immediately and sharply defines or indicates an undue increase of the gas ratio. The valve controlled by it puts into operation means to correct it by adding liquid to the intake. This is done on the theory that the

- increase in the gas ratio occurred thru a deficiency in the amount of liquid to make up the full load or capacity of the pump, but if the volume of gas is so great that at 5 the given discharge pressure the delivery or capacity of the pump is not great enough to handle the entire volume that would be made up by adding the amount of liquid required to make up the proper gas ratio, then 10 the second Pitot tube opens another valve which brings about a reduction in the delivery pressure. Then, the delivery pressure being lowered and a much higher gas ratio corresponding thereto prevailing, the 15 pump discharges the excess gas and returns to normal discharge pressure and corresponding gas ratio. If the gas ratio is still wrong, the sequence of operations is repeated. 20 The pump under normal conditions creates a certain difference in pressure between the intake and the discharge thereof. When the discharge pressure is released, the 25 pump is at once able to pull harder on the intake and handle a greater volume of gas. This intermittent action of higher and lower suction on the intake is a valuable feature of my invention as it will break an air lock such as often forms in a bend of the pipe 30 and which devices of the prior art are incapable of breaking.

As above intimated, one of the Pitot tubes is sensitive to such an increase of gas ratio as can be corrected by addition of liquid, 35 assuming the delivery head to remain the same, and the other Pitot tube is sensitive to such an increase of the gas ratio as would, if corrected by addition of liquid, overload the pump, and it therefore does not try to 40 correct the ratio, but instead drops the delivery head to a point where the prevailing gas ratio may be a proper ratio. Hence, I speak of the one Pitot tube being sensitive to conditions requiring more liquid to correct the gas ratio and the other as being sensitive to excessive delivery head for a high 45 gas ratio. While I employ Pitot tubes as elements sensitive to excessive gas ratio and to excessive delivery head, it is to be understood that I do not intend to limit the 50 invention to such specific means. These Pitot tubes are measuring devices for measuring certain physical variables corresponding to the phenomena which influence 55 operation.

In order to acquaint those skilled in the art with the manner of constructing and operating an embodiment of my invention, I shall now disclose a particular system 60 which I have constructed and operated and which embodies the invention.

In the accompanying drawings:

Fig. 1 is a side elevational view of a pumping and control system embodying the 65 invention;

Fig. 2 is a plan view of the same;
Fig. 3 is a side elevation taken from the left side of Figs. 1 and 2;

Fig. 4 is a longitudinal vertical section through the pump;

Fig. 5 is a horizontal section through the stuffing box and through the pump;

Fig. 6 is a diagram of the connections; and

Figs. 7 and 8 are explanatory diagrams 75 illustrating the general characteristics of the pump.

The tank 1 is divided into two compartments or chambers, the lower one 3 being the receiving tank or chamber and the upper 80 one 2 being the discharge tank or chamber. The tank 1 rests upon a suitable base 4 which may be connected to or independent of the pump and motor base 5, which is placed adjacent thereto. The pump and 85 motor base 5 provides a suitable mounting for the electric motor 6 and for the pump 7 and its connected parts. The motor 6 is connected to the pump 7 through a flexible coupling 8. The base 5 carries a pedestal supporting 90 a suitable bearing 9 between the motor and the pump, and this pedestal 10 has an integral ring or support 11 for receiving a boss 12 of the pump 7 for supporting said pump and its connected parts. Between 95 the bearing 9 and the pump support 11, I provide a suitable packing gland shown in detail in Fig. 5. This packing gland is normally covered by a cover or housing 13, as will be apparent from Fig. 2.

The pump 7 is of the type disclosed in my co-pending application, Serial No. 541,030, above referred to, but it differs therefrom in certain important aspects which are

employed herein as controls for determining the operation of the system. The pump comprises the runner 15, which is mounted upon shaft 16. The runner has a series of peripheral pockets, as indicated at 17 in Fig. 4, formed upon opposite sides of a central flange or ring 18, which ring is connected by spider arms 19 to the central hub 20.

The pockets are formed as lateral recesses in the periphery of the pump runner. This pump runner fits relatively closely in a peripheral groove or channel 21 formed in the pump casing. The pump casing is formed of a main back portion 22 and a cover member 23, said cover member 23 closing one side of the peripheral channel or recess 110 which is formed in the main body member 22. The body member 22 and the cover 23 have cooperating flanges 24 and 25 for bolting the two parts together, as by means of the bolt 26. The cover 23 has a conical inlet with a lateral opening 27 surrounded by a suitable bolting flange 28 adapted to

cooperate with a similar pipe flange 29 for the inlet pipe 30.

The gland which I have above referred 130

to is formed in the cylindrical boss 12 by which the pump is mounted in the support 11. A suitable counterbore 32 is formed in said boss 12 for receiving packing material 33, which may be of the well known fibrous or other character. A gland or sleeve member 34 has a reduced end fitting into the counterbore 32 to compress the packing 33 against the shaft 16. This sleeve 34 has, 10 in turn, an enlarged outer end 35 which is recessed, as indicated at 36, to receive packing material about the shaft 16, and a suitable gland member 37 is arranged to enter said counterbore 36 and compress the packing 33 therein for forming a second seal about the shaft 16. Between the two stuffing boxes and in the reduced portion of the sleeve member 34, I have provided a recess 38 which is adapted to be filled with a suitable 20 lubricating material, such as grease, as by means of a grease cup not shown connected to said space 38.

The gland 37 has a cross bar 38', the outer ends of which have slotted sockets, as indicated at 39 and 40, for receiving compression springs 41 and 42 which surround the gland bolts 43 and lie in said sockets 39 and 40. Suitable wing nuts 44 are mounted on the bolts 43 for compressing the springs 40 to 30 put the stuffing box and gland structure under suitable compression. The bolts 43 have square or noncylindrical heads 45 and are seated in suitable pockets or sockets 46, being thereby prevented from turning.

35 It will be apparent from the above description and from the drawings, particularly Fig. 5, that the bolts 43 may be very readily removed by compressing the springs 41 and 42 and raising the heads 45 out of the 40 sockets 46. Thereupon, the stuffing box structure may be disassembled by moving the parts to the left, as indicated in Fig. 5.

Now, referring to Fig. 4, I wish to call attention to the passageways 50 and 51 which 45 are formed in the pump casing. These passageways are formed in the main portion 22 of the pump, so that the cover may be machined substantially flat, although this is not of prime importance. The passageway 50 is the discharge passageway for liquid and 50 gas from the pump to the separator 52. This separator has a flange 53 at the bottom clamped to a flange 54 on the casing sections of the pump, and an opening or passageway 55 is formed in the lower part of said separator 55 with a baffle 56 to throw the discharge from the pump to one side to give the fluid discharged from the pump an opportunity to separate out its gaseous constituents from its liquid constituents. The 60 liquid tends to drop back into the lower portion of the separator 52 into the opening 57 and to pass out of the separator 52 through passageway 58, which communicates with 65 passageway 51 in the pump casing. The

lower end of passageway 51 terminates in a peripheral pocket in each of the casing halves, the pocket 59 in the casing half 22 being as shown in Fig. 4.

The pockets 59 extend a substantial distance radially along the pump runner, so as to give a suitable opportunity for liquid descending through the passageway 51 to fill the pump runner pockets 17, as they pass by the pockets 59.

75 The discharge passageway 50 terminates at its inner end in a peripheral opening 60, which opening extends a substantial distance along the periphery of the runner 15. This opening 60 provides a substantially tangential outlet for liquid from the pockets 17. Just beyond the opening 60, I have provided a baffle or vane 61 for stratifying the flow of discharge.

80 On each side of the vane 61 and mounted in the cover member 23, I have provided Pitot tubes 62 and 63 shown in dotted lines in Fig. 4. These Pitot tubes have openings facing downward in Fig. 4 towards the fluid as it is discharged from the pump, so that a 85 pressure will be caused in the Pitot tubes 62 and 63 bearing a certain relation to the velocity and inertia of fluid flowing out through the channels 64 and 65 on opposite sides of the vane 61.

90 In operation, the pump is initially primed with sufficient liquid to start operation, and with a priming charge such as may be secured by a trap in the intake, the pump will 95 operate to pump gas or liquid, in each case 100 maintaining a positive suction of relatively high value.

105 The pump, which I shall designate by the reference character 70, has its intake 30 connected to the lower or receiving tank 3 through two branches; namely, the branch 71 which leads to the bottom or low level point in the receiving tank 3 and a branch 72 which leads through an automatic pressure control valve 73 to the top or high level 110 point in the receiving tank 3. This valve 73 is adapted to be automatically opened by spring pressure and closed by fluid pressure, operating upon a fluid pressure element 74, 115 said element being connected by a small tube 75 with the Pitot tube opening 63 in the pump throat. The upper branch 72 which communicates with the top of the receiving tank 3 contains a T-connection for pipe 76 which leads to the ejector 77. This pipe 76 120 contains a check valve 78 to prevent flow of fluid in a downward direction in said pipe 76. The pipe 76 is adapted to convey gas or vapor from the top of the tank 3 to the ejector 77, which ejector is operated by liquid 125 discharged through the pipe 79 from the pump 70. The ejector 77 is adapted to discharge into the upper part of the discharge tank 2 through connection 80. A baffle, not shown, is provided in the upper tank 2 to 130

deflect the discharge of the ejector 77 away from the float 85.

The lower or receiving tank 3 is connected through a check valve 81 to the pipe 82, 5 which leads to the radiators of the heating system.

The discharge tank 2 has an upper air discharge connection 83 which is controlled by a valve 84 operated by float 85. Said discharge tank 2 also has a discharge connection 86 leading to the boiler for discharging water to the boiler through check valve 87.

Between the discharge connection 86 and the intake connection 82, I provide a bypass 88 controlled by a suitable valve 89. This valve is constructed like the valve 73 and it has its pressure controlled element 90 for closing the valve against the spring which tends to hold it normally open. 20 These automatic pressure control valves are articles of commerce and well known in the art. The pressure element of the valve 89 is connected by means of a small tube 91 to the Pitot tube opening 62 in the throat 25 of the pump.

The operation of the device is as follows: So long as the pump 70 is provided with an adequate supply of water and an amount of gas which will result in a gas ratio at or below the desired maximum, the pump operates to discharge a mixture of gas and water out of the throat 60, which mixture impinges against the Pitot tubes 62 and 63 and creates sufficient pressure in 30 the tubes 75 and 91, and in their connected pressure elements 74 and 90, to close the corresponding valves 73 and 89. Where the supply of the mixture of gas and liquid is inadequate to fill the pump discharge; 35 that is, when the gas ratio begins to increase beyond a desired maximum, then the flow through the channel 64 and past the Pitot tube 62 will decrease, with the result that the pressure in said Pitot tube 62 will drop 40 and the valve 90 will, under the influence of its spring, automatically open. The air which is being discharged from the pump through the channel 64 will be separated out in the separator 52 and the liquid will 45 run back through the opening 57, channel 58, passageway 51, into the pockets 59, charging the water back into the pumping or runner pockets 17 in the runner 15.

If the supply of liquid to the pump 70 further decreases; that is, if the intake gas ratio is further increased, then there will be a further diminution in the impact pressure of the mixture discharged through the channel 65, with the result that the flow or impact pressure will not be maintained on the Pitot tube 63. The result is that such deficiency of water to the pump will result in opening of the pressure control valve 73.

Now, with the above predetermined relations, I shall explain the normal operation

of the system. Assuming that steam is supplied to the radiators and that a suction is to be maintained upon the discharge of the same and that water of condensation is to be returned to the boiler, as indicated in the 70 diagram of Fig. 6. There is always a certain infiltration or leakage of air into the system and it is necessary to remove the same as the steam and water come in through the connection 82, past the check 75 valve 81 and into the receiving tank 3. The tendency in said tank 3 is for the gas and vapor which is created by the drop in pressure to rise to the top of the tank, and the liquid goes to the bottom of the tank 80 and will, while the pump 70 is running, be drawn through the low level connection 71 into the intake 30 of the pump, which is placed at about the level of the high level branch 72 which opens into the top of the 85 tank 3.

Assuming that while the pump 70 is in operation a suitable quantity of liquid in proportion to the air is drawn in through the connection 82 from the radiators, so that the gas ratio, that is, the ratio of gas to liquid, which arrives in the receiving tank 3 is within the normal working limit of the pump 70 for its proper efficiency, this mixture of gas and liquid will be withdrawn 90 from the tank 3 as it comes in from the pipe 82 and is discharged through the throat of the pump 70 through the receiver 52, pipe 79, past ejector 77, which is now inactive, and through the connection 80 into the 100 discharge tank 2, where the liquid drops to the bottom and the gas is separated out upwardly. During normal operation, the pressure on the discharge side of the pump is sufficient to discharge the liquid into the 105 boiler by way of the connection 86, check valve 87 and boiler feed pipe 86. Such pressure, we will assume, is around 15 pounds. In normal operation, the float valve 84-85 will be sufficiently opened to 110 throttle the discharge of air to maintain a suitable pressure upon the liquid to drive it into the boiler. This condition will continue during normal operation because it will be seen that if the pressure of the gas 115 on top of the liquid should suddenly decrease by too large an opening of the valve 84, then no liquid would be discharged into the boiler and the entering gas and liquid discharged by the pump 70 would raise the 120 level of liquid and shut off the valve 84, thereby restoring the pressure.

So long as the pump 70 is operating upon normal gas ratio, the pressure upon the Pitot tubes 62 and 63 will be great enough 125 to hold the respective valves 89 and 73 closed.

If, now, the gas ratio of the mixture into the receiving tank 3 and into the pump 70 increases to such a point where the impact

pressure measured in the throat channel 64 by the Pitot tube 62 is insufficient for maintaining the proper efficiency of the pump, the valve 89, which is a by-pass between the tanks 2 and 3, will now be opened permitting liquid to flow rapidly from the tank 2 to the tank 3. The extent of opening of the valve 89 will correspond to the drop in pressure upon the Pitot tube 62. The attempt made is to add sufficient liquid to the intake of the pump 70 to make up for the incorrect gas ratio; that is, to make up the deficiency in liquid so that the pump may operate upon a satisfactory efficiency.

Now, it will be appreciated that this addition of liquid cannot continue indefinitely, because to do so would be finally to overload the pump. The pump has only a certain capacity at a given delivery pressure or difference between intake and discharge pressure, and if the gas ratio cannot be corrected within that delivery, then the delivery pressure must be dropped or intake pressure must be raised. In the present case, the intake pressure cannot be satisfactorily changed because of the limitation of the vacuum system, and hence I provide the means in the shape of the by-pass valve 73 and the float valve 84 to lower the discharge pressure of the pump 70 so that a larger volume of mixture may be handled, and also so that a higher gas ratio for such volume may be employed.

I have illustrated, by a diagram in Fig. 7, the general character of the operation of the pump on differences of pressure on the intake and discharge side of the pump. That is to say, assume in the diagram of Fig. 7 that differences in pressure between the intake and discharge side of the pump are plotted as abscissa and that the discharge gas ratio values are plotted as ordinates; then the varying ratio can be illustrated by a graph or curve which is somewhat of the character illustrated in Fig. 7. That is to say, as the pressure difference is increased, the amount of gas which can be handled decreases rapidly, but as the pressure difference is lowered, the amount of gas which can be discharged is rapidly increased, and if the pressure difference becomes negative; that is to say, if an actual increase in pressure in the intake over the discharge exists, then the amount of gas which can be handled and the consequent gas ratio mounts very rapidly.

Now, assuming that the opening of the by-pass through the valve 89 has not corrected the gas ratio, then the impact pressure measured on the Pitot tube 63 drops to a point where the valve 73 opens and then temporarily the pump stops drawing liquid through the pipe 71 because the by-pass through the pipe 72 and the valve 73 has been opened.

This opening of the by-pass 73 tempo-

rarily stops the operation of the pump 70 so far as pumping liquid is concerned, and it will continue for a time to discharge air only or substantially hold delivery pressure without actually delivering any water to the tank 2. When the pumping of liquid stops, the liquid from the tank 2 flows through the valve 89 and begins to fill the tank 3, displacing the air therefrom. The difference in pressure between the tanks 2 and 3 assists this flow. During the interval which intervenes between the opening of the valve 73 and the raising of the liquid in the tank 3 to the level of the pipe 72; that is, the intake of the pump 70, the pump delivers air only and the level of the liquid in the tank 2 lowers while air is being driven out of the atmospheric connection 83. When the level in the tank 2 lowers sufficiently to open the valve 84, pressure in said tank 2 is dissipated by escape of the gases to atmosphere. The pump 70 then has only the atmospheric pressure to pump against, and a resulting increase in volume of discharge occurs.

This intermittent higher and lower gas ratio is accompanied by correspondingly decreased and increased drafts of the pump upon the suction line of the system. Such intermittent action is an important part of my invention because it will break an air lock which forms in certain parts of the pipe system. Such air locks are often very difficult to break by the devices of the prior art where such intermittent action is not provided.

As soon as the liquid in the tank 3 reaches the level of the intake pipe of the pump 70, the pump again takes up the discharge of liquid, immediately increasing the pressure on Pitot tubes 62 and 63 and closing the valves 89 and 73 respectively. At this time, while the atmospheric connection 83 is open at the valve 84, the discharge of a solid stream of liquid through the pipe 79 and ejector 70 results in drawing air from the top of the tank 3, through the connection 72 pipes 76, check valve 78 and out through the ejector 77, so that a relatively large amount of gas is ejected due to such lowering of the discharge pressure.

As soon as liquid has filled the tank 2 to the point of closing the atmospheric valve 84, then the pressure in the tank 2 increases to the point of discharging liquid through the check valve 87 to the boiler. The ejector 77 goes out of operation rapidly as the pressure is increased, and at normal operation; that is, when the normal gas ratio prevails, the ejector 77 does not function. Thus it will be seen that the ejector is only an auxiliary apparatus for securing a relatively large delivery of gas out of the tank 3 upon low delivery pressure of the pump. It is thus a supplementary device for securing large gas ratio upon low pressure differences.

upon the terminals of the pump for extending the normal characteristics of the pump itself.

The key to the entire operation is that of maintaining a proper gas ratio of the pump.

In Fig. 8, I have indicated the relation between intake gas ratio and impact pressure on the Pitot tubes 62 and 63. It will be seen that the normal impact pressure upon both

10 of these tubes is substantially equal when the pump is pumping solid liquid; that is, when the intake gas ratio is zero. As the intake gas ratio increases, the pressure on the Pitot tube 62 drops more rapidly than the pressure on the Pitot tube 63, with the result that the valve 89 is opened ahead of the valve 73, as is apparent from the curves shown in Fig. 8. I do not mean to say that these curves show any absolute values, 20 but merely the character of the relation.

The motor 6 which drives the pump 70 is controlled by a pressure sensitive element, so that when a predetermined drop in pressure has been created on the return system, 25 the motor is stopped and the pump thereby thrown out of operation until the pressure in the system has sufficiently raised or increased to require withdrawal of fluid from the system.

30 Now I wish to call attention to a peculiarity of the system illustrated. It will be seen that there is, first of all, a straight passageway from the steam return line 82 through the apparatus to the boiler feed pipe 86 and if solid liquid were discharged from the radiators into pipe 82, this would be pumped through the system without any local circulation. Next, I call attention to the fact that if gas alone were discharged 40 into the pipe 82, it would be pumped through the system and discharge to atmosphere at the pipe 83, employing, however, the internal liquid circulation of the pump itself, that is, the liquid going up through the discharge outlet 50 into the separator 52 and back 45 through the auxiliary inlet 51.

Now, if the gas ratio be decreased, the internal circulation within the pumping unit will decrease. It stops substantially completely when normal gas ratio is reached. Now, if however, the gas ratio increases after the pump has once been in normal operation, the by-pass 88 will open up, thereby creating the external circulation from the tank 2 to 55 the tank 3 in an endeavor to keep up the gas ratio to avoid the local or internal pump circulation. When the local or internal pump circulation occurs, the efficiency of the pump is low and consequently the external or tank circulation is substituted, as it will maintain a higher over-all efficiency of the pump and connected parts than if the pump had to rely upon its own local or internal circulation.

I do not intend to be limited to the details 60 shown or described, nor to the specific rela-

tions which I have indicated. It will be obvious to those skilled in the art that the controls which I have shown as automatic may be secured manually within the spirit of my invention, and it may be apparent to those skilled in the art that the controls which I have illustrated may be applied to different specific apparatus.

I claim:

1. In a system of the class described having a pump for pumping a mixture of gas and liquid at a predetermined ratio, the method of maintaining said ratio which comprises measuring the impact pressure of the mixture discharged by the pump and adding liquid inversely in accordance with the impact pressure to maintain the same substantially constant. 75

2. In a system of the class described having a pump for pumping a mixture of gas and liquid at a predetermined ratio for a given difference between intake pressure and delivery pressure, the method of maintaining the proper ratio which comprises measuring the gas ratio in terms of impact pressure of the mixture discharged by the pump and lowering the discharge pressure upon a predetermined increase of the gas ratio. 85 90

3. In a system having a pump for pumping a mixture of gas and liquid at a predetermined ratio for a predetermined difference between intake and discharge of the pump, the method of maintaining the proper gas ratio which comprises measuring the impact pressure of the discharge of the pump, 95 adding liquid to the intake of the pump as said impact pressure lowers, until the capacity of the pump is reached. 100

4. In a system having a pump for pumping a mixture of gas and liquid at a predetermined ratio for predetermined difference between intake and discharge of the pump, the method of maintaining the proper gas ratio which comprises measuring the impact pressure of the discharge of the pump, 105 adding liquid to the intake of the pump as said impact pressure lowers, until the capacity of the pump is reached, and then lowering the discharge pressure of the pump to enable it to work on a higher gas ratio. 110 115

5. In a system for pumping liquid with an admixture of gas, means for measuring the gas ratio of the mixture by its impact and means for correcting the gas ratio. 120

6. In a system of the class described, means for pumping a mixture of fluids from a given intake pressure to a predetermined discharge pressure, means for measuring the ratio of fluids pumped, automatic means acting upon a limited variation of said ratio to add a fluid to correct the ratio and automatic means acting upon a greater variation of said ratio to lower the discharge pressure. 125

7. In a system of the class described, a 130

5 pump, a vacuum system connected to the intake of the pump, a discharge connection for the pump, and means for opening the discharge to atmosphere when the proportion of gas to liquid delivered to the pump exceeds a predetermined value.

8. In a system of the class described, a pump, a vacuum system connected to the intake of the pump, a discharge connection for the pump, and means for decreasing the back pressure upon the delivery side of the pump when the ratio of gas to liquid exceeds a predetermined head.

11. In a pumping system employing a pump adapted to pump gas and liquid in a desired ratio, the method of maintaining the ratio which comprises admitting additional liquid to the intake as an inverse function of the impact head of discharge.

20. 10. In combination, a receiving tank, a connection for receiving gas and liquid into the tank, a discharge tank having separate gas and liquid discharge connections, a single pump for drawing fluids from the first tank and delivering them into the second tank, and means controlled by the inertia of the fluid discharge of the pump for controlling the discharge of the gas and for bypassing liquids from the second to the first tank.

33. 11. In combination, a receiving tank, a connection for receiving gas and liquid into the tank, a discharge tank having separate gas and liquid discharge connections, a pump for drawing fluids from the first tank and delivering them into the second tank, and fluid pressure operated means controlled by the level of liquid in the first tank for controlling the gas ratio of the fluid pumped from the said first tank.

40. 12. In combination, a receiving tank, a connection for receiving gas or liquid into the tank, a discharge tank having separate gas and liquid discharge connections, a pump for drawing fluids from the first tank and delivering them into the second tank, a by-pass from the second tank to the first tank, and fluid pressure operated means controlled by the level of liquid in the first tank for controlling said by-pass.

45. 13. In combination, a tank for receiving gas and liquid, a pump having its suction connected to the tank by one branch at a low level point and connected to the tank by another branch at a high level point, a valve for the high level connection and means controlled by lowering of the liquid to the low level connection for opening the high level connection to cause the pump to draw gas from the tank.

50. 14. In combination, a tank for receiving gas and liquid, a centrifugal pump capable of pumping either gas or liquid and having its suction connected to the tank by one branch at a low level point and connected

to the tank by another branch at a high level point, a valve for the high level connection and means controlled by lowering of the liquid to the low level connection for opening the high level connection to cause the pump to draw gas from the tank.

55. 15. In combination, a tank for receiving gas and liquid, a centrifugal pump pumping a normal mixture of gas and liquid from said tank, and means controlled by low level liquid in the tank for causing the pump to pump a greater ratio of gas than normal.

60. 16. In combination, a tank for receiving gas and liquid, a centrifugal pump capable of pumping a predetermined ratio of gas and liquid from said tank, means controlled by insufficient flow of liquid into the tank for causing a reduction of the delivery pressure of the pump, and means controlled by high level of liquid in the tank for causing the tank to pump a mixture of gas and liquid having a gas ratio of greater value.

65. 17. In combination, a tank for receiving gas and liquid, a centrifugal pump connected to the tank capable of pumping a mixture of gas and liquid against a predetermined delivery head, an ejector supplied with liquid by the discharge of liquid from the pump for drawing gas from the tank, said ejector being ineffective when the pump is pumping the normal mixture of gas and liquid, and means controlled by diminution of the liquid discharged from the pump for lowering the discharge head of the pump to enable the ejector to draw gas.

70. 18. In combination, a receiving tank adapted to be maintained under suction, a centrifugal pump capable of pumping a mixture of gas and liquid connected to said tank, an ejector on the discharge side of said pump, said ejector having its suction connected to the top of said tank, said ejector being normally inoperative while the pump is pumping its normal ratio of gas and liquid at its normal delivery head, and means controlled by lowering of liquid level in the tank for putting said ejector into operation.

75. 19. In combination, a receiving tank, a centrifugal pump capable of discharging liquid and gas, a receiving tank connected to the discharge of said pump, separating means for separating gas from liquid in said discharge tank, and means controlled by insufficient liquid in the receiving tank for causing the pump to drop its delivery pressure and discharge a mixture of gas and liquid with a greater gas ratio.

80. 20. In combination, a receiving tank, a centrifugal pump having its intake mounted at substantially the same level as the upper part of said receiving tank, a connection from the upper part of the receiving tank to the intake, a connection from the lower part of the receiving tank to the intake, a

pressure controlled valve governing said upper connection, and a pressure connection from the discharge of said pump to said valve for closing said valve when liquid ⁵ has risen to the upper connection.

21. In combination, a receiving tank having a high level connection and a low level connection, a centrifugal pump having its intake mounted at substantially the level ¹⁰ of the high level connection and being also connected to the low level connection, a valve in the high level connection, and pressure operated means controlled by discharge of liquid from the pump for closing the ¹⁵ high level connection.

22. In combination, an upper tank having automatic air and water separating and discharging means, a receiving tank having a suction inlet, a valved by-pass between tanks, ²⁰ a pump having a suction connection into the lower tank and a discharge connection into the upper tank, and pressure operated means controlled by emptying of the lower tank of liquid for opening the valved by-²⁵ pass.

23. In combination, a closed receiving tank, a pump capable of pumping gas and liquid, said pump being connected to the tank, means for delivering to the tank gas ³⁰ and liquid, a closed discharge tank, means controlled by lowering of the liquid level in the receiving tank below a predetermined value for opening the discharge tank to atmosphere.

35. 24. In combination, a closed receiving tank, a pump capable of pumping a mixture of gas and liquid, said pump being connected to the tank, means for delivering to the tank gas and liquid, means controlled by lowering ⁴⁰ of the liquid level below a predetermined value for causing the pump to lower its discharge pressure, and means controlled by rise of the liquid level to a predetermined point to cause the pump to pump a larger ⁴⁵ proportion of gas and then raise its discharge pressure.

25. In combination, a closed receiving tank, a pump capable of pumping a mixture of gas and liquid, said pump being connected ⁵⁰ to the tank, means for delivering to the tank gas and liquid, auxiliary means comprising an ejector in the discharge of the pump for withdrawing gas from the top of the tank, said ejector being normally ineffective, and ⁵⁵ means to render said ejector effective when the proportion of gas to liquid discharged into the receiving tank is high.

26. In combination, a receiving tank, a pump capable of pumping gas and liquid ⁶⁰ connected to said tank, an ejector connected in the discharge of the pump and having a suction connection to the top of the tank, and means for causing the pump to operate the ejector to draw gas from the tank only

when the intake gas ratio in the receiving ⁶⁵ tank is higher than normal.

27. In combination, a receiving tank, a pump capable of pumping gas and liquid connected to said tank, an ejector connected in the discharge of the pump and having a ⁷⁰ suction connection to the top of the tank, means controlled by an abnormally high gas ratio to provide a supplementary inflow of liquid into the tank, and means controlled by continued abnormality of gas ratio for ⁷⁵ actuating the ejector to withdraw gas from the tank.

28. In combination, a tank for receiving gas and liquid, a pump capable of pumping gas and liquid from said tank, an ejector in ⁸⁰ the discharge side of the pump for drawing gas from the tank, and automatic means for lowering the discharge pressure of the pump to actuate the ejector when the gas ratio becomes abnormally high. ⁸⁵

29. In combination, an upper tank having automatic air and water separating and discharging means, a receiving tank having a suction inlet, a valved by-pass between said tanks, a pump having a suction connection ⁹⁰ into the lower tank and a discharge connection into the upper tank, and pressure operated means controlled by emptying of the lower tank of liquid for opening the valved by-pass. ⁹⁵

30. In combination, an upper tank and automatic air discharge connection and liquid discharge connection therefor, a lower tank, a suction line therefor, a by-pass between said tanks, a valve for said by-pass, ¹⁰⁰ a single pump capable of pumping either gas or liquid or both, said pump being connected between the lower tank and the upper tank, and automatic means controlled by the character of the fluid discharge from the pump for controlling said by-pass. ¹⁰⁵

31. In combination, an upper tank serving as a separator of liquid and gaseous fluids, means for automatically discharging gaseous fluid, means for automatically discharging liquid from said upper tank, a lower tank, a gravity by-pass between said tanks, a valve in said by-pass, a pump for pumping fluids from the lower tank and discharging them into the upper tank, and means governing the opening of the valve when the liquid in the lower tank drops below a predetermined level. ¹¹⁰ ¹¹⁵

32. In combination, a suction line, a lower tank communicating with the line, an upper tank, a by-pass between the tanks, a pressure control valve in the by-pass, a rotary pump capable of pumping gas and liquid from the lower tank to the upper tank, an outlet for gas from the upper tank, a liquid discharge connection from the upper tank, and valve means controlled by the discharge of liquid through the pump for closing said by-pass. ¹²⁰ ¹²⁵

33. In combination, a pump for pumping a mixture of gas and liquid at a predetermined gas ratio and against a predetermined delivery head, an intake system connected to the intake of the pump, a discharge system connected to the discharge of the pump, and means in the discharge of the pump sensitive to an excessive gas ratio for adding liquid to the intake system.
34. In combination, a pump for pumping a mixture of gas and liquid at a predetermined gas ratio against a predetermined delivery head, an intake system connected to the intake of the pump, a discharge system connected to the discharge of the pump, means in the discharge of the pump sensitive to an excessive gas ratio for adding liquid to the intake system and sensitive to a further increase in the gas ratio for dropping the pressure in the discharge system to permit the pumping with a gas ratio higher than normal.
35. In combination, a pump for pumping a mixture of gas and liquid at a predetermined gas ratio against a predetermined delivery head, an intake system connected to the intake of the pump, a discharge system connected to the discharge of the pump, and means sensitive to an excessive gas ratio in the intake for adding liquid to the intake system.
36. In combination, a pump for pumping a mixture of gas and liquid at a predetermined gas ratio against a predetermined delivery head, an intake system connected to the intake of the pump, a discharge system connected to the discharge of the pump, means sensitive to an excessive gas ratio of the intake for adding liquid to the intake system, and means sensitive to a further increase in the gas ratio for dropping the pressure in the discharge system to permit the pumping with a gas ratio higher than normal.
37. In combination, a pump for pumping a mixture of gas and liquid at a predetermined gas ratio against a predetermined delivery head, an intake system employing an intake trap connected to the intake of the pump, a discharge system employing a discharge trap connected to the discharge of the pump, means sensitive to an excessive gas ratio for opening a by-pass between the discharge trap and the intake trap for adding liquid to the intake system of the pump.
38. In combination, a pump for pumping a mixture of gas and liquid at a predetermined gas ratio against a predetermined delivery head, an intake system employing an intake trap connected to the intake of the pump, a discharge system employing a discharge trap connected to the discharge of the pump, means sensitive to an excessive gas ratio for opening a by-pass between the discharge trap and the intake trap to add liquid to the intake of the pump, and means sensitive to a further increase in the gas ratio for connecting the discharge trap with atmosphere to drop the pressure in the discharge system to permit pumping with a gas ratio higher than normal.
39. In a pumping system for a steam heating plant having a return line, the combination of a self priming pump having an intake connected to the return line and having a discharge connection, and means for controlling the back pressure in the discharge connection to vary intermittently the suction upon the intake connection.
40. In a pumping system for a steam heating plant having a boiler feed line and a return line, a self priming pump adapted to pump gas and liquid from the return line, a separator for separating gas and liquid connected to the discharge of the pump, said boiler feed line being connected to the separator for the discharge of liquid, and means for intermittently opening said separator to atmosphere to reduce the back pressure upon the pump and thereby intermittently increase the suction upon the return line.
41. In a pumping system for a steam heating plant having a boiler feed line and a return line, a self priming pump adapted to pump gas and liquid from the return line and discharge the liquid to said boiler feed line and means for intermittently bypassing the discharge of the pump to the intake and to atmosphere to increase the pumping of gas from the return line.
42. In a system for pumping liquid and gas, a pump, means responsive to decrease of delivery of the pump for sharply decreasing the back pressure upon the pump.
43. In a system for pumping a liquid and a gas, a self priming pump and means for decreasing the delivery pressure on the pump and simultaneously increasing the suction upon the intake of the pump.
44. In a system for pumping a mixture of gas and liquid, a self priming pump, means controlling the ratio of gas to liquid passing through the pump, and means for decreasing the delivery pressure on the pump and simultaneously increasing the suction upon the intake when the pump is called upon to deliver a higher gas ratio.
45. In a heating system having a return pipe, a gas and liquid pump and a boiler feed pipe connected to the discharge of the pump, the method of breaking an air lock in the return pipe which comprises temporarily releasing the discharge pressure upon the pump and thereby increasing the suction upon the return pipe.
46. In a pumping system, a gas and liquid pump, a return line connected to the intake of the pump, a pressure discharge line for the pump and means controlled by the rate of delivery of the pump for releasing the

discharge pressure to increase the pumping of gas from the return line.

47. In combination, a steam return line, a centrifugal liquid and gas pump capable of creating a predetermined difference of pressure between said lines and means for automatically releasing the pressure upon the discharge line to break an air lock in the steam return line.

48. In combination, a steam return line, a pressure discharge line, a centrifugal liquid and air pump capable of creating a predetermined difference of pressure between said lines for a given delivery of liquid and gas

15 at a given gas ratio and means for automatically increasing the gas ratio when the delivery drops off.

49. In combination, a steam return line, a pressure discharge line, a centrifugal liquid and gas pump capable of creating a predetermined difference of pressure between said lines for a given delivery of liquid and gas at a given gas ratio and means for automatically decreasing the delivery pressure when the delivery of the pump drops off.

50. In combination, a steam return line, a pressure discharge line, a centrifugal liquid and gas pump capable of creating a predetermined difference of pressure between said lines for a given delivery of liquid and gas at a given gas ratio and means for automatically increasing the delivery of the pump when the gas ratio decreases.

51. In a device of the class described, a single pump having an intake and a discharge connection, said pump being capable of pumping a predetermined delivery of both gas and liquid at a predetermined gas ratio at a predetermined difference of pressure between intake and discharge, and means controlled by deviation of one of said predetermined conditions from normal for by-passing a part of the liquid from the discharge connection to the intake.

52. In a device of the class described, a pump having an intake and a discharge connection, said pump being capable of pumping a predetermined delivery of gas and liquid at a predetermined gas ratio and at a predetermined difference of pressure between intake and discharge, and means controlled by deviation of one of said predetermined conditions from normal for automatically varying another condition to compensate for the deviation.

53. In a system of the class described, a return pipe, a boiler feed pipe, a centrifugal pump having an intake connected to the return pipe, an impeller, a separating chamber connected to the discharge from the impeller and a return connection from the separating chamber to the impeller, a separating tank connected to the discharge of the separating chamber, a by-pass connection from the tank to the intake of the pump, means

for automatically controlling said by-pass to maintain a suitable gas ratio through the pump, the return connection being active to return liquid to the impeller only when the gas ratio is excessive.

54. In combination, a suction pipe, a pressure delivery pipe, a centrifugal pump for pumping gas and liquid, said pump having an impeller and an internal return circuit comprising a liquid and gas separator, and an auxiliary inlet for returning liquid from the separator to the impeller, a gas or liquid discharge connection leading from the top of said separator to the delivery pipe, a gas and liquid separating tank in said connection and an automatically controlled by-pass between the liquid space of the separating tank and the suction pipe.

55. In a system of the class described, a self priming pump having a suction pipe and a discharge pipe, a by-pass between said pipes, said pump having a divided discharge throat and means governed by the pressure in one division of said throat for controlling said by-pass.

56. In a system of the class described, a self priming pump having a suction pipe and a discharge pipe, a by-pass between said pipes, said pump having a divided discharge throat and means governed by the pressure in one division of said throat for controlling said by-pass, means in the intake for accumulating liquid and delivering only gas to said pump, said means being controlled by the pressure in the other division of said throat.

57. In combination, an upper tank, a delivery pipe leading therefrom, a lower tank, a return pipe leading thereto, a single pump having its suction connected to the lower tank and its discharge to the upper tank, a connection between the tanks, a valve therefor, and means controlled by the impact of the liquid delivered from the pump to control said valve.

58. In combination, a receiving tank for gas and liquid, a separating tank for separating gas and liquid above the first tank, a centrifugal pump between the tanks, said pump having its intake connected to the lower tank and its discharge connected to the upper tank, a connection between said tanks, a valve controlling said connection, means controlled by the gas ratio of the fluid discharged by said pump for operating said valve to permit liquid to flow from the upper tank to the lower tank.

59. In combination, a receiving tank for receiving gas and liquid, a pump having a suction inlet connected to the receiving tank, a separating tank for gas and liquid connected to the discharge of the pump, said separating tank being above the receiving tank, means to discharge liquid from the upper tank to the lower tank when the

- supply of liquid in the receiving tank is abnormally low, and an air discharge connection connected to the upper part of the receiving tank for discharging air from the receiving tank, and means to stop the effective pumping action of the pump until the liquid in the lower tank reaches a predetermined level.
60. In combination, a receiving tank, a connection for receiving gas and liquid into the tank, a discharge tank having separate gas and liquid discharge connections, and a single centrifugal pump for drawing simultaneously under suction gas and liquid from the first tank and delivering them simultaneously under pressure into the second tank.
61. The method of withdrawing fluid from a vapor heating system and returning the condensate to the boiler, which comprises creating a flow of the condensate from said heating system, causing said condensate to entrain uncondensable gas, discharging the condensate and gas under pressure, separating the gas from the liquid under pressure, discharging a portion of the liquid under pressure to the boiler, and returning a portion sufficient to maintain the flow substantially constant.
62. In combination, a receiving tank, a connection for delivering gas and liquid into the tank, a discharge tank for receiving under pressure the entire discharge from the pump, said tank having separate gas and liquid discharge connections, and a single self-priming centrifugal pump for pumping gas or liquid or both under suction from the first tank and delivering the same under pressure to the second tank.
63. In combination, a steam return line, a pressure discharge line, a single centrifugal liquid and gas pump capable of creating a predetermined difference of pressure between said lines for a given delivery of liquid and gas at a given gas ratio, and means for automatically by-passing from the pump discharge to the pump suction a part of the liquid to increase the total amount of gas delivered without proportionally increasing the total amount of liquid delivered.
64. In combination, a centrifugal pump capable of pumping gas and liquid comprising a casing, a runner therein, a discharge passageway, a vane in the discharge passageway for stratifying the fluid discharged by the impeller according to its density, Pitot tubes disposed in said discharge passageway on opposite sides of the vane, and means responsive to the difference in pressure upon said Pitot tubes for controlling the ratio of gas and liquid admitted into the casing of the pump.
65. In combination, a centrifugal pump capable of pumping gas and liquid in a predetermined ratio at a given pressure difference, means for supplying gas and liquid at a variable ratio to the intake of said pump, and means sensitive to the gas ratio of the mixture pumped for controlling said supplying means.
66. In combination, a centrifugal pump capable of pumping gas and liquid comprising a casing, a runner therein, a divided discharge passageway for stratifying the discharge of the pump according to density, a Pitot tube in one of the divisions of said discharge passageway and means responsive to the pressure on the Pitot tube for measuring the gas ratio of the discharge of the pump.
67. In combination, a centrifugal pump capable of pumping gas and liquid comprising a casing, a runner therein, a divided discharge passageway for stratifying the discharge of the pump according to density, and means responsive to the difference in impact pressure of the fluid in the divisions of said passageway for measuring the gas ratio of the discharge of the pump.

In witness whereof, I hereunto subscribe my name this 21st day of February, 1924.

HARRY E. LA BOUR.
